UNITED STATES PATENT OFFICE.

EARL B. HOUGH, OF STOCKTON, CALIFORNIA, ASSIGNOR TO IRVINE AND HOUGH COMPANY, OF STOCKTON, CALIFORNIA, A CORPORATION.

AUTOMATIC SELF-ADJUSTING PNEUMATIC-MUSIC-PLAYER ACTION-VALVE.

No. 894,007.

Specification of Letters Patent.

Patented July 21, 1908.

Application filed November 5, 1907. Serial No. 400,785.

To all whom it may concern:

Be it known that I, EARL B. HOUGH, a citizen of the United States, residing at Stockton, in the county of San Joaquin, State of California, have invented certain new and useful Improvements in Automatic Self-Adjusting Pneumatic-Music-Player Action-Valves; and I do declare the following to be a full, clear, and exact description of the same, such as will enable others skilled in the art to which it appertains to make and use the same, reference being had to the accompanying drawings, and to the characters of reference marked thereon, which form a part of this application.

This invention relates to music players and particularly to that type known as pneumatic, my object being to provide a valve mechanism which will automatically operate in accordance with the pneumatic action of the device on which it is installed and unseat and reseat itself automatically and in a thorough and effective manner. Also one which will be simple and inexpensive of construction, and one which can be easily installed and repaired if necessary. These objects I accomplish by means of a valve suitably seated and having a stem so disposed as to permit said valve to oscillate freely in respect thereto; also by a correlative construction and arrangement of parts whereby the said valve will operate in accordance with the pneumatic action thereof; also by such other and further construction as will appear by a perusal of the following specification and claims.

In the drawings similar characters of reference indicate corresponding parts in the several views.

Figure 1 is a side elevation of a piano key showing my improved pneumatic valve mechanism connected therewith. Fig. 2 is an enlarged sectional view of the pneumatic action mechanism. Fig. 3 is a sectional view taken relatively on a line $\alpha\alpha$ of Fig. 2. Fig. 4 is a sectional view of a valve. Fig. 5 is a fragmentary detached view of valve stem and pivot.

Referring now more particularly to the characters of reference on the drawings 1 designates a key of the instrument having an adjustment screw mechanism 2 connecting the same with the push rod 3.

4 is a dowel slidably disposed beneath the rear of the key 1 and having a pin 5 extend-

ing through an arm 6 secured to the bottom of a bellows 7 secured to a structure 8.

9 is an air passage leading from the bellows 7 into a chamber 10 from which chamber 10 a port 11 leads to the atmosphere and passages 12 lead into a vacuum chamber 13.

14 is an opening from the chamber 13 into a chamber 15 over which opening 14 is disposed a flexible diaphragm 16. Also disposed from the chamber 13 to the chamber 15 is a small bleed hole 17. Disposed in the chamber 10 normally over the air passages 12 is a valve 18 having leather 19 on its top and leather 20 on its lower end. Said valve is provided with a central socket 21 through which is extended a pin 22. Hung on said pin 22 is a valve stem in such manner as to permit the said valve to oscillate freely with respect to said stem, said stem extending through a slot 12^a, which acts as a guide therefor, into the chamber 13 and having a disk 24 normally seated on the diaphragm 16. 25 is an opening leading from the chamber 13 to the main suction mechanism of the instrument, while 26 is a pipe leading from said chamber 15 to the usual tracker board 27 over which runs the usual record sheet 28.

29 is a sheet of strong paper or similar material which forms the cover for the exposed ends of the chambers 13 and 15 for a purpose as will appear.

In practice the above described mechanism is of course connected with each and every key. When this mechanism is in its normal position the suction through the opening 25 exhausts all the air from the chamber 13 by means of the opening 25, and from chamber 15 and pipe 26, through bleed hole 17, thus creating a vacuum therein. This causes the diaphragm 16 to be sucked tight into the opening 14, thus permitting the valve 18 to be pulled close over the passages 12, the leather 20 preventing any air passing into the chamber 13. In this position the bellows 7 receives a full supply of air through the passages 9 and 11, thus holding the dowel 4 normally out of engagement with the key 1. Then when a perforation in the paper 28 passes over the slot in the tracker board 27 the vacuum in the chamber 13 suddenly draws a quantity of air into the chamber 15, thereby forcing the diaphragm 16 and disk 24 upward, unseating the valve 18 from the passages 12 and closing the port 11 by means of the leather 19 on said valve 18, thus per-

mitting the vacuum in the chamber 13 to draw all the air from the bellows 7 through the passage 9, chamber 10 and passages 12 into said chamber 13, thus causing the bellows 7 to close, driving the dowel 4 upward, and thus engaging the key 1, causing it to suitably operate the hammer mechanism and produce music. Then when the said perforation passes off the tracker board, closing the slot therein, the suction through the opening 25 exhausts the air from the chamber 15 through bleed hole 17 as has been described, the diaphragm 16 resuming its normal position, thus permitting the valve 18 to reseat itself over the passages 12. In this connection the main feature of my invention is the fact that the valve 18 is capable of freely oscillating with respect to its stem 23 which permits it to adjust itself automatically and perfectly over the passages 12, thus preventing any possibility of air getting into the chamber 13 until it is desired. Owing to valve stem 23 being attached to valve 18, which valve 18 is given a free oscillation on valve stem 23, as described, the said valve 18 is pulled back and seated over openings 12 by the downward suction of diaphragm 16, thus giving the valve 18 a rapid and positive motion without depending on springs or gravity and by the oscillation of valve 18 it will seat itself at any angle at which seats containing openings 12 and 11 might be with relation

to each other. When the valve 18 has reseated itself as described the bellows again fill with air through the port 11 and passage 35 9, thus carrying the dowel 4 out of engagement with the key 1, as described.

Thus it will be seen that I have produced such a device as substantially fulfills all the objects of the invention as set forth herein.

While this specification sets forth in detail the present and preferred features of the construction of my device, still small deviations therefrom may be resorted to; none of which will, however, form a departure from the spirit of the invention.

Having thus described my invention, what I claim as new and desire to secure by Letters Patent, is:

In a device of the character described, a structure having a plurality of chambers, there being air passages connecting the same, a valve seat over one of said passages and comprising a head having a socket formed therein, a pin disposed through said socket, a stem pivoted on said pin, said head being capable of freely oscillating with respect to said stem, as set forth.

In testimony whereof I affix my signature in presence of two witnesses.

EARL B. HOUGH.
